UNITED STATES PATENT OFFICE

MICHAEL GILSON, OF PORT WASHINGTON, WISCONSIN, ASSIGNOR TO KWIK-MIX CONCRETE MIXER CO., OF PORT WASHINGTON, WISCONSIN

MIXER.

Application filed December 22, 1926. Serial No. 156,401.

This invention relates to mixers, and is particularly directed to a means of fastening the arms for the mixer blades to the shaft.

In mixers as heretofore constructed, particularly plaster mixers, it has been the universal custom to provide the arms with relatively large cast hubs which have to be secured to the shafts. These hubs are necessarily relatively large in order to provide for the passage of the shaft therethrough. In actual practice, these hubs collect the material and form knobs or balls of material of relatively large size which materially interfere with the efficient working of the mixer.

This invention is designed to overcome the defects noted above, and objects of such invention are to provide a mixer in which the arms for the mixing blades are secured to the shaft without the use of hubs and without any material enlargement at the shaft, and to provide such a construction that the securing means itself strengthens the arms and forms in effect a reinforcement therefor.

Further objects are to provide an extremely simple type of device for securing the arms to the shaft and one which may be most cheaply constructed and easily applied.

The latter feature noted above is of material importance when, for example, it is necessary to remove the hub to replace parts of the apparatus it becomes necessary to slide the hub off the shaft. This is a very difficult operation, particularly if the shaft has become rusted or otherwise roughened or coated. With this invention, however, this defect is wholly overcome as it is not necessary to slide the attaching means from the shaft as the attaching means is so made that it is merely necessary to open the hub and remove it laterally from the shaft.

An embodiment of the invention is shown in the accompanying drawings in which:

Figure 1 is a fragmentary view of a portion of a mixer shaft and the associated arms and blades;

Figure 2 is a sectional view on the line 2--2 of Figure 1.

Referring to the drawings, it will be seen that the mixer shaft is indicated by the reference character 1, and the mixing blades by the reference character 2. These mixing blades may be either straight or curved as shown in the drawings, and in the particular form shown, are peculiarly adapted for the mixing of plaster, although of course, the mixer can be used for other purposes without departing from the spirit of this invention.

The blades 2 are formed of sheet metal strap, as are the arms 3 which extend radially from the shaft to the blades and are securely bolted to the blades, as indicated at 4. The central or inner portions of the arms 3 are bowed outwardly to provide semi-cylindrical parts 5 which enclose the shaft 1, as shown most clearly in Figure 2. These semi-cylindrical parts continue outwardly and form short ears 3'. A pair of key pieces or key bars 6 are positioned between the arms 3 and the ears 3' and are securely bolted in place by means of bolts 7 passing through the arms and key pieces and by means of bolts 8 passing through the ears, the key pieces, and the arms.

It is to be noted that the key pieces project inwardly of the cylindrical portions 5 and extend into key-ways 9 formed in the shaft, thus securely keying or locking the arms 3 to the shaft. It is to be noted further that these key pieces strengthen the arms 3 at the point where they leave the shaft and, consequently, at the point where the greatest strain occurs.

It is to be distinctly understood that the key pieces may be formed double, but a single key piece may be used, if desired. However, in the form shown, the members 3 may be of identical construction, and may be readily stamped and the double key piece insures the utmost security of attachment between the arms and the shaft.

These mixers have heretofore been constructed with relatively large cast iron hubs at the point where the shaft passes through the arms, and these hubs have had to be

slipped upon the shaft and also from enlargements of a material size which collect plaster or other material and interfere with the efficient operation of the device. It is 5 clear that this invention overcomes these defects as it does not require the use of hubs at the points where the shaft passes through the arms. Instead, there is very little additional thickness over the diameter of the 10 shaft at these points. Further than this, the arms themselves are greatly strengthened by this construction so that the key pieces not only serve to attach the arms rigidly to the shaft, but also have the additional function of materially reenforcing 15 the arms.

It will be seen further that the parts may be most easily stamped or otherwise cheaply formed and may be placed in position and bolted securely with the utmost facility, and 20 in the minimum time.

Although the invention has been described in considerable detail, such description is intended as illustrative rather than limiting 25 as the invention may be variously embodied and as the scope of such invention is to be determined as claimed.

I claim:

The combination of a shaft having diametrically opposed key ways, a pair of arms having arcuate portions adjacent one end and adapted to embrace opposite sides of the shaft, with the shorter end of one arm lying parallel with the longer end of the other arm, flat key pieces having their inner 30 ends engaged within the key ways and extending parallel with the arms, a pair of bolts extending through the long and short portion of the arms at one side of the shaft 35 and through the key pieces, and a second pair of bolts extending through the longer portion of each arm and through the key pieces adjacent the outer ends thereof.

In testimony that I claim the foregoing 40 I have hereunto set my hand at Port Washington, in the county of Ozaukee and State 45 of Wisconsin.

MICHAEL GILSON.
